Term of patent 14 years

(Cl. D58—17)

FIG.1

FIG.4

FIG. 1 is a perspective view of a packaging container for food or the like showing my new design;

FIG. 2 is a side elevational view thereof;

FIG. 3 is a bottom plan view thereof;

FIG. 4 is an enlarged fragmentary view of a portion of FIG. 2.

The dominant features of my design reside in the portions shown in full lines and consists of the particular beveled scallops adjacent the lower edge substantially as shown.

I claim:

The ornamental design for a packaging container for food or the like, as shown and described.
